UNITED STATES PATENT OFFICE.

JOHN CORNWELL ROUND, OF LONDON, ENGLAND.

BOX OR CRATE.

1,338,533.

Specification of Letters Patent. Patented Apr. 27, 1920.

Application filed September 27, 1919. Serial No. 326,806.

To all whom it may concern:

Be it known that I, JOHN CORNWELL ROUND, subject of the King of Great Britain, residing at "Purbrook", Crescent Wood 5 Road, Sydenham Hill, London, S. E., 26, England, have invented new and useful Improvements in Boxes or Crates, of which the following is a specification.

This invention has reference to crates or 10 boxes which can be taken to pieces for package and storage purposes, the object being to produce a "breakdown" box or crate which is simple in construction and which will occupy the minimum of space 15 when stored or packed away, and also facilitate the return of empty cases or crates.

According to my invention when forming the parts of the box or crate, that is to say—the sides, ends, lid, and bottom of wood, 20 cardboard, or like material, I provide each part with a metallic or other flange or groove (one edge of which acts as a flange) fixed or secured to two of their opposite edges, the other two opposite edges remaining 25 plain so that when these parts are assembled the plain edges of the one part are slipped by or fit into the flanged or grooved edge of the adjacent parts, each part being locked on its plain edges by the flanges or 30 grooves on the edges of the adjacent parts. The sixth part—that is the lid or cover, is enabled to be placed into its correlative 35 position by forming one of the flanges or sides of the groove of an adjacent part so as to hinge, and when such lid or cover is 40 so placed it is fixed or held by the hinged flange or side of the groove being secured in a right angle position to the said lid by any suitable means. Or adjacent sides may 45 each have a flange hinged for this purpose. Or instead of hinging a flange or groove of one or two of the parts adjacent to the lid or cover I accomplish the same purpose by forming the parts constituting the lid or 50 cover with a strip or portion of one of its plain edges loose so that the opposite edge can be slipped under the flange of the one adjacent side and then the loose strip passed under the flange of the other adjacent side. Or 55 one of the flanges on one of the adjacent sides may be made detachable for this purpose.

In order to enable the five parts forming the crate or box to be held together before 55 the lid or cover is fixed thereon to permit the same being filled I provide suitable

catches or equivalent on the parts constituting the sides and ends which temporarily hold them in position until finally locked by the lid or cover.

60

When constructing the parts of a box of metal the flanges or grooves may be formed on the two edges of such parts by press tools, or they may be made independently and secured to the two edges of the parts. 65 I may also strengthen or stiffen the plain edges of the parts by forming a bead or strengthening flange thereon, and such bead or strengthening flange may act as the temporary medium for holding the parts in 70 position while being assembled and while filling or packing.

The invention is illustrated on the accompanying drawings.

Figure 1 is a perspective view of a box 75 constructed according to this invention.

Fig. 2 is a view of the detached parts of a box showing five of the parts packed together.

Fig. 3 is a view of one of the metallic 80 flanges showing the inner face of the portion which is fixed to one of the edges of the inner face of one of the parts of the box.

Fig. 4 is a view showing the inner face of 85 the free portion which embraces the edge of the adjacent part of the box.

Fig. 5 is a back view of one of the grooves.

Fig. 6 is a front view of Fig. 5.

90

Fig. 7 is an inner view of one of the parts of a crate with a metallic flange forming two of its opposite edges.

Fig. 8 is an edge view of one of the ends of a crate.

95

Figs. 9 to 15 inclusive show details of various parts and modifications.

Figs. 16 and 17 show parts of a metallic box constructed according to this invention.

Figs. 18 to 20 inclusive show details of 100 other parts.

A represents the sides, B the ends, D the bottom, and E the lid or cover of a box made of wood. Fixed or secured in any suitable manner to two of the opposite edges 105 of each part is a metallic flange F. These flanges may be right angle flanges as shown by Figs. 2, 3, and 4; or grooves as shown by Figs. 5 and 6, or T shape as shown by Fig. 9^b, and are fixed to the inner surface of the 110 opposite edges of each part, so that when the parts are assembled the flanges on the

ends B lap over or bear against the plain edges of the sides A, the flanges on the bottom D and those on the lid or cover E lap over or bear against the plain edges of the ends B, and the flanges on the lower edge of the sides A overlap or bear against the plain edges of the bottom D; and in order to enable the sixth part, that is the lid or cover E to be placed in its correlative position one or both of the flanges on the upper edges of the sides A are made to hinge as shown by Figs. 1 and 2. When such lid or cover is so placed it is fixed or held by its hinged part of the flange or flanges being secured in a right angle position to said lid in any suitable manner.

For the purpose of enabling the five parts forming the crate or box to hold together before the lid or cover E is fixed thereon to permit the same being filled I provide suitable catches or other devices on the parts A and B. On the drawing I have shown a device consisting of a key-hole slot f' formed near the upper and lower end of that part of the flange F which is secured to the two edges of the ends B, and secured to the plain edges of the sides A is a projection a' (see Fig. 10) the head of which passes freely through the large part of the slot f' , but when the parts of the box are in position the head fits at the back of the narrow portion, thereby temporarily holding such parts together until the lid or cover is fitted thereon, when they are finally locked together. Other means for temporarily holding the parts A, B, and D may, however, be employed.

When using grooves instead of right angle flanges the plain edges of the adjacent part fit into the grooves. At Figs. 13 and 14 I have shown an example of this method of construction as applied to a box the sides of which are of greater length than the ends. It will be found, especially when such boxes are made of thin wood or other light material, that the grooves prevent the sides of the box from being crushed inward, thereby preventing any likelihood of the contents being damaged.

At Fig. 11 I have shown another method of enabling the lid or cover E to be placed into its correlative position and secured or fixed. In this case instead of making one of the flanges F on one or both of the upper edges of the sides A to hinge I cut a strip e' off one of the plain edges of said lid or cover, which strip, after placing the remaining portion of said lid or cover in position, can be slipped under the flange F on the side A and over the free ends of the flanges on the lid or cover, thus holding the parts firmly together. Or I may make one of the flanges F on one of the adjacent edges of the sides A detachable and capable of sliding into and engaging with a metallic strip fixed

to this edge of said side A, as shown by Fig. 12. The loose bar or strip e' or the detachable flange may be fixed or locked when in position by any suitable means.

If desired instead of fixing the right angle flanges F to the inner surfaces of the opposite edges of the parts A, B, D, and E such flanges may be formed so as to be fixed to the outer surface of said parts, as shown by Fig. 9. The key-hole slots f' in this case engaging with studs a' secured to the outer surface of the adjacent parts. Or the flanges F may be made from a flat strip of metal, wood, or other material and secured to the opposite edges of the parts A, B, D, and E in the manner shown by Figs. 9a. Or when using wood flanges, such flanges may be secured to the opposite edges of the inner surface of said parts.

When making the parts of a box or crate from two, three or more ply wood, fiber, or other material I may protect the edges of such parts with a right angle protecting flange f^2 as shown by Fig. 18. Or the protecting flanges may be grooved as shown by Fig. 19.

At Figs. 16 and 17 I have shown an example of the parts of a box made of metal, the flanges or grooves F being formed on the opposite edges of said parts by suitable press tools. Or such flanges or grooves may be made separately and secured to the opposite edges of each part. I may also stiffen the plain edges of the parts by forming a bead f^3 or equivalent on such edges, and such beading may act as the temporary medium for holding the parts of the box in position while being assembled and while filling or packing the contents, as shown by Fig. 17. The hinged flange on one or both of the upper edges of the sides A may be formed of wire as shown by Fig. 16. The hinged flanges whether formed of wire or otherwise may be usefully employed as a means for lifting the box or crate, provision being made in such flanges when solid for this purpose.

As an additional security for holding the flanges F on their respective parts when made of wood or like material I may form prongs or projections on the surface of that part of the flange by punching out portions of the metal or otherwise.

At Fig. 20 I have shown how the spaces at the corners of a box made according to this invention may be filled in by a block of rubber or other suitable material.

What I claim as my invention and desire to secure by Letters Patent is:—

A collapsible box, comprising ends, a top, and a bottom, each having inwardly projecting flanges on two of its opposite edges which overlap the plain edges of the adjacent part, sides having inwardly projecting flanges which overlap the bottom of the

box, plates hinged to the sides and foldable over the top of the box, means for securing the said plates to the top, and detachable means for temporarily locking the ends of 5 the box to its sides before the sides are secured to the top.

In testimony whereof I have signed my

name to this specification in the presence of two subscribing witnesses.

JOHN CORNWELL ROUND.
